US0D1013875S

(12) **United States Design Patent** (10) **Patent No.:** **US D1,013,875 S**
(45) **Date of Patent:** **** Feb. 6, 2024**

(54) **SPINAL IMPLANT**(71) Applicants: **restor3d, Inc.**, Durham, NC (US);
Duke University, Durham, NC (US)(72) Inventors: **Andrew Todd Miller**, Durham, NC (US); **Matthew Rexrode**, Durham, NC (US); **Cambre Kelly**, Durham, NC (US); **Ken Gall**, Durham, NC (US)(73) Assignees: **RESTOR3D, INC.**, Durham, NC (US);
DUKE UNIVERSITY, Durham, NC (US)(***) Term: **15 Years**(21) Appl. No.: **29/780,309**(22) Filed: **Apr. 23, 2021****Related U.S. Application Data**

(62) Division of application No. 29/719,880, filed on Jan. 8, 2020, now Pat. No. Des. 920,515.

(51) **LOC (14) Cl.** ..... **24-03**(52) **U.S. Cl.**USPC ..... **D24/155**(58) **Field of Classification Search**USPC **D24/155, 231**
CPC **E03C 1/00; A61L 2/00; A61L 9/00; A61L 9/22**

See application file for complete search history.

(57) **CLAIM**

The ornamental design for a spinal implant, as shown and described.

DESCRIPTION

FIG. 1 is a perspective view of a spinal implant showing my new design;

FIG. 2 is a top plan view thereof;

FIG. 3 is a bottom plan view thereof;

FIG. 4 is a left-side elevation view thereof;

FIG. 5 is a right-side elevation view thereof;

FIG. 6 is a front elevation view thereof; and,

FIG. 7 is a rear elevation view thereof.

The broken lines illustrate portions of the spinal implant and form no part of the claimed design.

1 Claim, 7 Drawing Sheets
